GARMENT HANGER

Margaret M. Brock, Middle Village, N. Y.

Application January 4, 1949, Serial No. 69,209

1 Claim. (Cl. 223—89)

1

This invention relates to garment hangers, and particularly to an article of this character which is telescopically collapsible or capable of being materially reduced in size to thereby permit of the same being adjustable to accommodate garments of various sizes, and also to render it extremely portable and of small size and capable of being carried or contained in small space, thus rendering it convenient for travelling.

An object of the invention is to provide a garment hanger of the above character which may be made of wire and thus be made economically and inexpensively by readily-available machinery.

More particularly, the invention contemplates the provision of a garment hanger having a frame wholly composed of wire and having a central portion hung from a suspension hook and receiving end portions which are slidably adjustable toward one another on the central portion to thereby either reduce the overall size of the hanger or else extend it to full or to intermediate size as required.

The invention further contemplates the provision of other features of construction to be hereinafter set forth and more particularly pointed out in the claim appended hereto.

In the accompanying drawing, wherein an illustrative embodiment of the invention is disclosed, Fig. 1 is a front elevation of a garment hanger constructed according to the invention and in its extended, or fully open position; Fig. 2 is a front elevation of the garment hanger in its collapsed or telescoped position; Fig. 3 is a sectional view taken on the line 3—3 of Fig. 2, looking in the direction of the arrows; Fig. 4 is a view of one of the end members of the hanger; Fig. 5 is a view of the central supporting member, and Fig. 6 is a perspective view of one of the end members.

The hanger includes a triangular wire frame which is composed of four main parts, namely, the central supporting member 1, the end members 2 and 3, and the suspension hook 7. All of the parts of the hanger are preferably composed of relatively stiff wire which may be bent to the desired shapes by known wire-forming machinery. The central support 1 consists of a single piece of wire and is formed with the two legs 4 and 5 extending divergently from the centrally located loop 6 which receives a loop formed on the lower end of the suspension hook 7. At the free end of each of the legs 4 and 5 is formed a guide loop or eye 8.

The end members 2 and 3 are both alike in con-

2

struction and a description of one of them will suffice for both. Each of said end members consists of a bent length of wire which may be described as being roughly U-shape, having a lower longer leg 11 and an upper shorter leg 9. At the end of the leg 9 is formed a laterally-bent guide loop or eye 10 and at the end of the long leg 11 is formed a laterally-bent guide loop or eye 12.

In the assembled position of the parts of the hanger, it will be observed that each of the short legs 9 on the end members 2 and 3, extends and is guided through one of the loops or eyes 8 on the legs 4 and 5 of the central member 1. These legs 4 and 5 extend respectively through the loops or eyes 10 provided on the legs 9 of the end members 2 and 3. The long leg 11 of one of the end members extends through the guide loop 12 on the long leg of the companion end member, as clearly seen in Figs. 1 and 2.

The open or extended position of the hanger is shown in Fig. 1, wherein it will be seen that the hanger, when so extended, is of the normal shape and size of the conventional wire coat hanger. When it is desired to reduce the size of the hanger or to collapse or telescope it compactly for packing it in a hand bag or otherwise transporting it, the end members 2 and 3 are pushed inwardly or toward one another to either the limit of such movement or to any extent desired to reduce the hanger to the size required. When pressure is imposed on the end members 2 and 3, they will slide along the legs 4 and 5 of the central member, and the guide loops 12 will also slide on the legs 11 which they respectively embrace, thus permitting the end members 2 and 3 to move inwardly or toward one another to the limit of such movement, if desired. The hanger in its fully telescoped or collapsed condition is shown in Fig. 2 wherein it will be noted that the same has been very materially reduced in size and may thus be readily accommodated in a hand bag or in any other small space.

The parts of the hanger are, as previously stated, composed of springy wire and are preferably arranged to slide rather stiffly relatively to one another so that they will remain in any set position. This will enable the hanger to be partially collapsed, when desired, to enable it to accommodate small garments such as children's garments. When the hanger is in its fully telescoped condition, as seen in Fig. 2, it may be further reduced in size, if desired, by folding the suspension hook 7 downwardly, and by springing the parts slightly, causing the hook 7 to engage about the legs 11. This will flex the legs 11

slightly and thus prevent inadvertent sliding movement of the parts of the wire frame relatively to one another and serve to hold the hanger in its collapsed or telescoped condition.

The construction of the hanger is such that its parts may be easily fabricated at small cost; it is sturdy and convenient to use and when telescoped or collapsed can be very conveniently carried in luggage, in the pocket, or in the glove compartment of an automobile, thus providing the advantages of having a garment hanger present without utilizing space normally required for a hanger of conventional construction.

Having described one embodiment of the invention, it is obvious that the same is not to be restricted thereto, but is broad enough to cover all structures coming within the scope of the annexed claim.

What I claim is:

A garment hanger having a central wire piece, 20 said piece having legs extending divergently from its center, said piece being formed with a central loop, each leg being formed at its end with an eye, a pair of U-shaped wire end members, each of said end members having a relatively short leg slidable through one of the eyes, each short leg terminating in an eye through which

5 one of the legs of the central wire piece is slideable, each of the end members having a long leg, said long legs overlapping and forming an adjustable cross bar for the hanger, said long legs terminating in eyes by means of which said long legs slidably embrace one another, and a suspension hook swingably attached to the loop of the central piece, said hook being of a length to enable it to be swung to a position to engage about the adjustable cross bar when the hanger is collapsed and apply tension thereon to prevent the sliding movement of the legs which form said bar.
